UNITED STATES PATENT OFFICE.

EVA R. BARTLETT, OF PASADENA, CALIFORNIA.

BOTTLE CLOSURE.

Application filed December 23, 1924. Serial No. 757,633.

This invention relates to improvements in bottle closures.

The object of the invention is to provide an improved bottle closure having means adapted to extend into the bottle so that when the closure or cap is removed the contents of the bottle within the neck may be sufficiently stirred or loosened to facilitate removing of the contents of the bottle. The improved closure is especially adapted to be used in connection with catsup bottles and similar semi-fluid substances.

With the foregoing and other objects in view which will be made manifest in the following detailed description, and specifically pointed out in the appended claims, reference is had to the accompanying drawing, wherein—

Figure 1 is a side elevation of a bottle, parts being broken away to show the improved closure as applied thereto.

Fig. 2 is an enlarged vertical section through a portion of the improved closure.

Fig. 3 is a horizontal section taken substantially upon the line 3—3 of Figure 1.

Referring to the accompanying drawings, wherein similar reference characters designate similar parts throughout;

A suitable cap 10 may be threaded onto or otherwise secured upon the neck 11 of a bottle B. A member 12, preferably formed of sheet metal or the like, is secured upon the underside of the cap 10 and has its ends bent downwardly, as at 13 and 14, so as to be disposed within the neck 11. The ends 13 and 14 of the member 12 are provided with angular extensions 15 and 16 respectively, which extensions in the preferred form of construction, are bent slightly inward so that they are not concentric within the neck 11, as clearly shown in Fig. 3.

The lower edge of each of the extensions 15 and 16 is curved outwardly, as indicated at 17, so that the inside of each of the extensions is somewhat dished. The member 12 may be soldered or otherwise secured upon the underside of the cap 10 and a cork ring or similar gasket forming structure, as indicated at 18, may be disposed about the member 12 upon the under side of the cap 10.

The operation of the improved closure is as follows:

Frequently the semi-fluid contents of bottles becomes thickened in the neck of the bottle so that it is difficult to pour the con-

tents therefrom. When the cap 10 is unscrewed or removed from the neck 11, preferably by an upward rotary motion, the members 13 and 14, together with the dished extensions, rotate within the neck as they are being withdrawn. Because of the shape of the members 13 and 14 and of the dished extensions 15 and 16, the contents within the neck is sufficiently stirred to insure its fluidity, so that the contents may be readily poured through the neck.

As clearly shown upon the drawings, the members 13 and 14 bear against the interior of the neck for substantially their complete length. In bottles containing semi-fluid substances such as ketchup and the like, the substance tends to thicken and harden against the interior surface of the bottle, consequently upon the rotation of the cap the members 13 and 14 bear against the interior surface of the bottle and loosen this substance which tends to stiffen and adhere to the interior of the bottle.

From the above it is seen that an improved bottle closure is provided, consisting of a cap having a member secured thereto which extends downwardly within the neck of the bottle, which member is adapted to stir up the contents of the bottle upon being withdrawn, thus facilitating the pouring of the contents through the neck.

It will be understood that various changes may be made in the details of construction without departing from the spirit or scope of the invention, as defined by the appended claims.

I claim:

1. A bottle closure comprising an imperforate cap adapted to be secured about the neck of a bottle, a member secured to said cap and extending downwardly within the neck of said bottle when said cap is in applied position, said member presenting a dished surface adjacent its lower end.

2. A bottle closure comprising an imperforate cap adapted to be secured about the neck of a bottle, a member secured to said cap and extending into said neck, and an angular extension secured adjacent the end of said member within said neck, said extension presenting a dished surface substantially as shown and described.

3. A bottle closure comprising an imperforate cap adapted to be secured about the neck of a bottle, a member secured upon the

under side of said cap, said member having its ends bent downwardly within the neck of the bottle when said cap is in applied position, said ends being provided with angular extensions, said angular extensions being dished as and for the purpose described.

4. A bottle closure comprising an imperforate cap adapted to be secured about the neck of a bottle, a member secured upon the under side of said cap, said member having its ends bent downwardly within the neck of the bottle when said cap is in applied position, said ends being provided with angular extensions, said angular extensions presenting dished surfaces, and a cork ring secured upon the under side of said cap about said member.

5. A bottle having a neck on the top of which is mounted an imperforate cap, a member secured to the cap and extending downwardly within the neck when the cap is in applied position, said member being so arranged as to bear against the interior of the neck substantially its complete length when in applied position, and means providing a lateral extension on the bottom of

the member which is disposed adjacent the interior surface of the bottle.

6. A bottle having a neck on the top of which is mounted an imperforate cap, members secured to the cap and extending downwardly into the interior of the bottle when the cap is in applied position, said members being so arranged as to bear against the interior of the bottle for substantially their complete length, and means providing lateral extensions adjacent the lower ends of said members which are disposed adjacent the interior surface of the bottle.

7. A bottle closure comprising a cap, and a strip of sheet material secured centrally to the under side of the cap, said strip having its ends bent downwardly to provide two substantially straight members adapted to bear against the interior surface of a bottle when the cap is applied thereto for substantially their complete length, whereby upon rotation of the cap said members will scrape against the interior surface of the bottle.

In testimony whereof I have signed my name to this specification.

EVA R. BARTLETT.
